UNITED STATES PATENT OFFICE.

HAROLD POTTER DONLE, OF MERIDEN, CONNECTICUT, ASSIGNOR TO THE CONNECTICUT TELEPHONE & ELECTRIC COMPANY, INCORPORATED, OF MERIDEN, CONNECTICUT, A CORPORATION OF CONNECTICUT.

RADIOFREQUENCY DEVICE.

Application filed April 7, 1921. Serial No. 459,304.

To all whom it may concern:

Be it known that I, HAROLD P. DONLE, a citizen of the United States of America, residing at Meriden, New Haven County, Connecticut, have invented a new and useful Radiofrequency Device, of which the following is a specification.

The main object of my invention is to provide a simple, inexpensive, efficient, and durable means for generating, amplifying, or detecting alternating currents, and particularly those of radio frequencies. Another object is to provide apparatus of this type in which the element which in time becomes exhausted or depleted is as simple and inexpensive as possible. Another object is to provide a vacuum tube device which is itself capable of creating radio frequency oscillations, and also one in which the control and selection of the frequency is dependent upon the constants of the vacuum tube device itself and which does not depend upon the constants of any associated oscillatory circuit.

In its preferred form, the vacuum tube contains only an axially arranged filamentary cathode. The tube is preferably cylindrical and provided on its exterior surface with an anode. A coil surrounds the anode and is preferably movable longitudinally of the tube. The coil is preferably supplied with current from the same battery that heats the cathode. The tube is preferably surrounded by a shield to prevent fluctuations due to changes of temperature. The construction of the tube and coil and the circuit arrangements will be more fully understood from the following description and the accompanying drawings:

Fig. 1 is a diagrammatic view of the device with a simple form of generating circuit.

Fig. 2 is a side view and partial longitudinal section of the tube device and coil.

Fig. 3 is an end view of the coil and support without the tube.

Fig. 4 is a side view of a tube with a shield in section.

Fig. 5 is a diagrammatic view showing my invention embodied in a receiving circuit.

Fig. 6 is a diagrammatic view of a circuit

arranged for observation of the phenomena of the tubes' operation.

The filament 10 is enclosed in a vacuum tube 11 which is surrounded by an anode 12. The coil 13 surrounds the tube and anode and is preferably spaced apart therefrom.

The battery 14 supplies current for heating the cathode and also for energizing the magnet coil 13 and impressing a positive potential upon the anode. A variable resistance 15 is employed in the cathode circuit for modifying the current through the filament, and a variable resistance 16 is employed in the coil circuit for modifying the current producing the magnetic field. A potentiometer 17 is bridged across the battery for modifying the anode voltage. An inductance 18 may be included in the anode circuit. Oscillations produced by the device, with or without this inductance 18, may be impressed upon another circuit, e. g., an antenna or other radiating circuit. Telephone receivers may be substituted for 18, as shown in Figs. 5 and 6, and oscillations may be impressed upon the tube, either as shown in Fig. 5 or by the absorbing action of the tube and the circuits. It should be noted that the frequency of the tubes' oscillations is substantially independent of the value of this inductance.

The glass shield 19 having ventilating openings such as 20 is preferably interposed between the coil and the tube.

One end of the filament 10 is supported by a bracket 21. Connection is made to the anode by a yoke 22. The tube 11 and the circuit terminals for the cathode and anode are carried by the base 23 which may also be conveniently used as a support for the shield 19. For convenience in mounting the tube and its base, I provide an insulating member 24 with a socket 25. This member 24 may conveniently have a series of circuit terminals 26, 27, 28 and 29, and also have supporting rods 30 and 31 for slidably supporting the coil. For convenience in making the electrical connections, I may provide spring contacts such as 32 and 33 to which the ends of the coil are connected. These contacts sliding on the rods 30 and 31 maintain electrical connections as the coil is adjusted by means of the thumb nut 34 which

2
screws on the rod 31 and operates in opposition to the spring 35. The thumb nut 34 may have a dial 34' for indicating the rotation so as to enable the operator to set 5 the coil and reset the coil at the desired position with relation to the anode and cathode.

In the receiving circuit of Fig. 5, 36 represents the conventional antenna with an inductance and capacity. 37 is the companion inductance in circuit with the tube and constituting a secondary inductance coupled to the antenna circuit. This inductance 37 is shunted by a variable condenser 38, the combination forming a reservoir circuit 15 which may be used to augment the intensity of the oscillations generated by the tube, although it does not control their frequency. A stopping condenser 39 may also be provided. 40 is a standard high resistance telephone which may be shunted by a condenser 41. A choke coil 42 may be used or omitted. My device may also be used as a receiver or transmitter without any capacity inductance or turning circuit, in which case I may connect the antenna directly to the anode 12 and ground the negative terminal of the battery.

Fig. 6 shows certain elements in common with Figs. 1 and 5 numbered correspondingly. 43 indicates a meter for indicating the filament current. 44 is a meter for indicating the magnetic field current. 45 is a meter for indicating the anode potential. 46 is a meter for indicating the anode current.

35 Without intending to be limited, but in order to fully disclose conditions pertinent to my invention, I will now proceed to describe the relative dimensions and electrical condition of apparatus shown in Fig. 6 used 40 in making certain tests for demonstrating the operation of my invention.

The filament was a molybdenum wire .004 of an inch in diameter, in the form of 45 48 turns wound on a form .02 of an inch in diameter and stretched out to a length of 1 inch. The approximate length of the wire in the filament was $3\frac{1}{2}$ inches. The tube itself was of glass of an external diameter of approximately $9/32$ of an inch at the part 50 surrounding the cathode. The glass was a sodium silicate glass with lime and approximately $1/32$ of an inch thick. The tube was exhausted as completely as possible with commercial apparatus. The anode was in 55 the form of a silver deposit in intimate contact with the glass and co-extensive longitudinally with the cathode. The coil was formed of No. 24 enameled wire, wound in ten layers, approximately $27/16$ inches in 60 length, and with the interior of the coil approximately 1 inch in diameter, making approximately 1150 turns, and with a resistance of 9.8 ohms. The potential of the battery was 6 volts. Throughout the tests the 65 filament current was .885 amperes.

With a magnet field current of .405 amperes and the coil arranged over the tube so that its lower end was approximately on a plane with the lower end of the anode, as shown in Fig. 2, a potential of 4 volts applied to the anode produced an anode circuit current of approximately 56 microamperes. Under these conditions the device oscillated at a frequency of about 328,000 cycles per second, corresponding to a wave length of 75 about 912 meters. By screwing down the adjusting nut 34 and moving the coil so as to bring the anode nearer the center of the coil, the anode current was gradually reduced until at a position of the coil one-half inch lower than shown in Fig. 2, the anode current was approximately 28 microamperes. As the anode approaches the center of the coil the anode current falls off more slowly. It will be obvious that instead of 80 moving the coil the tube itself might be moved within the coil, since a relative motion of the coil and tube is all that is necessary. The relative movement of the coil and tube as above described resulted not only in 85 a reduction of the anode current, but in an increase in oscillating frequency and a corresponding decrease in wave length; for instance, at the second position of the coil above mentioned, the wave length was approximately 700 meters, corresponding to a 90 frequency of 428,000 cycles per second.

By fixing the coil in position and varying the current through the coil, somewhat similar changes in anode current and oscillation 100 frequency may be produced; for instance, with the same filament current .885 amp. and anode potential 4 volts, and with a coil position intermediate the two above described positions, and with a coil circuit current of .35 amperes, the anode current was 105 56 microamperes and the wave length was about 880 meters. By increasing the magnetic circuit current to .5 amperes, the anode current fell off to about 19 microamperes 110 and the wave length decreased to approximately 650 meters.

The foregoing tests might indicate that the wave length was a direct function of the anode current, but tests in which the 115 filament current, magnetic coil current, and coil position were held constant and the anode potential was varied, show the contrary. For instance, with the same filament 120 current as before and the same coil position as in the preceding paragraph, and with the magnetic coil current fixed at .405 amperes an anode potential of 3.5 volts produced an anode current of about 24 microamperes. Under these conditions the tube produced 125 oscillations corresponding to a wave length of 780 meters. By increasing the anode potential to 5.5 volts the anode current was increased to approximately 98 microamperes and at the same time the oscillation fre- 130

quency was increased corresponding to a wave length of 715 meters. Under some conditions however the wave length does not change uniformly with changes in anode potential.

Many of the tests which I have made indicate that with an anode potential above 5.5 volts the particular device described became more or less unstable. An excessive 10 magnetic field strength is, I believe, detrimental to the operation of the device.

It will be clear, however, that the various constants of the tube will vary with the dimensions and materials employed, and I 15 have given the foregoing figures simply to illustrate the general construction and mode of operation of the device, without intending to be limited to any particular set of constants.

20 One of the advantages of the invention is that the device remains sensitive even if the battery employed weakens. This may be due to the interrelation of the elements operating on a common battery under the conditions set forth.

With the apparatus herein described, as above demonstrated it is possible to obtain continuous oscillations of controllable radio frequencies without the use of a capacity 25 inductance circuit. We are able to alter the period of oscillation by alteration of either the strength or position of the magnetic field or the strength of the electric field between anode and cathode. It will be seen 30 that the movement of the coil materially affects the frequency at a given filament current. It should also be understood that changes in the temperature of the filament affect the wave length.

40 By the use of my invention it is possible to utilize a relatively small tube and a minimum volume of metal within the tube in the cathode and its support. As a result of this small size, there is a minimum possibility 45 of gas emanations which are so detrimental to permanent and stable operation of tubes having internal anodes or plates and control elements or grids. It should also be understood that the device may be used in other 50 circuit arrangements than those herein illustrated, and that I do not consider the broad invention limited to the materials or proportions herein specified.

I claim:

- 55 1. In a device of the character described, a vacuum tube, a cathode contained therein, an anode in intimate contact with the outer surface of the tube and connected to said cathode, and an adjustable magnetizing coil surrounding said anode outside of said tube.
- 60 2. In a device of the character described, a vacuum tube, a cathode therein, a source of current for said cathode, an anode on the outside of said tube connected to said cathode, and means external of said anode for

impressing a magnetic field upon the space within said tube, and means for varying said field independently of the cathode current.

3. In a tube of the character described, a vacuum tube, a cathode contained therein, 70 an anode on the outside of said tube connected to said cathode, and means co-acting with said cathode and said anode for generating radio frequency oscillations in said tube, said means being independent of any 75 associated oscillation circuit for controlling the period of oscillation of said tube.

4. In a device of the character described, a vacuum tube, a cathode contained therein, an anode on the outside of said tube, a coil 80 for impressing a magnetic field upon said tube, and a single battery for simultaneously energizing the cathode and said coil.

5. In a device of the character described, a vacuum tube, a cathode contained therein, 85 an anode on the outer surface of said tube, a source of direct current for heating said cathode, said anode being connected to said cathode exteriorly of said tube, and an energizing coil in parallel circuit arrangement 90 with said cathode, whereby radio frequency oscillations the frequency of which is independent of any associated oscillation circuit are generated.

6. In a device of the character described, 95 a vacuum tube, a cathode therein extending longitudinally thereof, an anode on the outer surface of said tube co-extensive in length with said cathode and connected thereto, a coil surrounding said anode, and a source of direct current for said cathode, anode and coil whereby the device is inherently productive of oscillations.

7. In a device of the character described, a vacuum tube, a cathode therein, a non-magnetic anode surrounding said tube and connected to said cathode exteriorly of said tube, and means for impressing a controllable magnetic field upon said tube.

8. In a device of the character described, 110 a vacuum tube, a cathode therein, a cylindrical anode in intimate contact with the outer surface of said tube and substantially co-extensive with said cathode, and a coil surrounding said tube and said anode and adjustable longitudinally with relation thereto.

9. In a system of the character described, a vacuum tube, a cathode contained therein, an anode surrounding said tube and connected to said cathode, a coil surrounding 120 said anode, a source of current for said cathode and for said coil, and an antenna inductively connected to said anode.

10. In a system of the character described, a vacuum tube, a cathode therein, an anode exterior to said tube and connected to said cathode, a translating device connected to said anode, and means for impressing a magnetic field upon said tube.

11. In a device of the character described, 125

a vacuum tube, a cathode contained therein, a non-magnetic anode on the outside of said tube, a magnetizing coil surrounding said tube, means for supporting said coil, and means for supporting said tube whereby said tube is removable independently of said coil.

12. In a device of the character described, a vacuum tube, a cathode therein, an anode on the outside of said tube connected exteriorly to said cathode, and a coil surrounding said tube and connected to said cathode.

13. A non-regenerative source of radio frequency oscillations, comprising a vacuum tube, suitable circuits associated therewith, a cathode therein, an anode exterior to said

tube and connected to the cathode, and means for impressing a magnetic field upon said elements.

14. A non-regenerative source of radio frequency oscillations, comprising a vacuum tube, a cathode therein, an anode exterior to said tube and connected to said cathode, means for impressing a magnetic field upon said elements, and an antenna circuit associated therewith. 25

15. A non-regenerative source of radio frequencies, comprising a vacuum tube, a cathode therein, an anode on the outside of said tube, and a coil surrounding said anode.

HAROLD POTTER DONLE.
